RAILWAY SIGNAL CONTROL CIRCUIT

Frank H. Nicholson, Penn Township, Allegheny County, Pa., assignor to The Union Switch & Signal Company, Swissvale, Pa., a corporation of Pennsylvania

Application November 30, 1940, Serial No. 367,973

12 Claims. (Cl. 246—38)

My invention relates to circuits for controlling railway signals and it has special reference to the utilization by such circuits of the "coded feed back" operating principle that first was disclosed by my patent No. 2,021,944 (issued November 26, 1935) and that also is shown by numerous later patents and applications of common ownership herewith.

Broadly stated, the object of my invention is to improve the organization of the apparatus which supplies the conductors of such circuits with pulses of "feed back" energy that recur in step with the "off" period intervals of the "master" control circuit code.

A more specific object is to facilitate the control of feed back energy applying relays of the "impulse" type which devices IR of Herman G. Blosser Reissue Patent No. 21,783 (granted April 29, 1941) exemplify.

Another object is to simplify the structure and increase the power economy of the pick-up circuits for such impulse relays when those relays are used in systems wherein the "master" energy operated code following relay is supplemented by a code following repeater, such as is shown (at TR) in Fig. 3 of the Blosser reissue patent above named.

In practicing my invention I attain the above and other objects and advantages by: (1) eliminating all "transformer" devices from the impulse relay pick-up circuit; (2) carrying this circuit directly over a back contact of the "master" energy operated code following relay; and (3) serially including in this circuit a contact of a repeater relay which is closed when the code following relay is picked up and which opens after a slight delay upon each code following relay release.

I shall describe three forms of feed back energy supply apparatus embodying my invention and shall then point out the novel features thereof in claims. These illustrative embodiments are disclosed in the accompanying drawing in which:

Fig. 1 is a diagrammatic representation of a track type of control circuit equipped with the improved feed back supply apparatus of my invention and organized to form part of an automatic block signaling system having "coded feed back" approach lighting control;

Fig. 2 is a representation of "master" and "feed back" codes for the control circuit of Fig. 1;

Fig. 3 is a partial reproduction of the feed back supply apparatus of Fig. 1 showing how the impulse relay pick-up circuit thereof is modified

upon change of the repeater relay from a back to a front contact controlled device; and

Fig. 4 shows feed back supply apparatus wherein in the "master" code following relay is rendered unresponsive to the "off" period feed back pulses by means external to the impulse relay.

In the several views of the drawing like reference characters designate corresponding parts. Referring first to Fig. 1, the improved control circuit organization of my invention is there disclosed in association with a coded track circuit system of automatic block signaling for a railway track 1—2 over which it will be assumed that traffic moves in the single direction indicated by the arrow, or from left to right in the diagram. The protected stretch of this track is divided into the customary successive sections by insulated rail joints 3 and the rails of each section form part of a track type of control circuit which normally is capable of transmitting energy between its two ends but which at times is rendered incapable of such transmission.

In this view of Fig. 1 reference characters D and E respectively designate the entrance and the exit ends of one of these track sections which is illustratively shown as being a full signal block in length; character TR designates a code following track relay which is installed at the entrance end of the section and operated by energy received from the rails thereof; character TB is a track battery or other "master" energy source provided at the section exit for the purpose of supplying these rails with the relay operating energy just referred to; character CTM a coding device having a contact 5 which codes this energy by periodically interrupting the rail supply circuit; and character S the usual wayside signal which guards the entrance of each of the track blocks and which is controlled by the associated track relay TR through the medium of a repeater relay TM and decoding apparatus DA.

An automatic block signaling system of the referred to coded track circuit type operates without the aid of line wires and in the representative form that is disclosed by Fig. 3 of the earlier identified Blosser Reissue Patent No. 21,783 it includes all of the elements above named. Such a system further comprises the customary facilities (not shown in Fig. 1) for continuously operating each of the exit end relays CTM at one or another of the usual plurality of distinctive code rates. Selection among these rates (which in a typical three-indication system may consist of 75 and 180 energy pulses per minute) is made in accordance with advance traffic con-

ditions by the decoding apparatus DA functioning in customary manner.

This decoding apparatus (details not shown in Fig. 1) is controlled in the usual fashion by the code following repeater relay TM and it performs the further function of selectively setting up a lighting circuit for one or another of the signal lamps (G, Y and R in the typical three-indication system above referred to) of the wayside signal S at the same location.

Typically, such decoding apparatus requires that the code following relay which controls it make use of a plurality of contacts and in Fig. 1 two such contacts are indicated at 6 and 7. As might be expected, however, this multiplicity of contacts causes the decoding control relay to require an increased amount of operating energy.

When the track sections of the signaling system are comparatively short, energy of this increased intensity can quite readily be transmitted (from the exit end source TB) to the relay directly over the section rails 1-2 and contacts 6-7 may then be carried by the rail-energized track relay TR. In such short track circuit applications, accordingly, repeater devices of the character shown at TM obviously are not needed.

When, however, the length of the track circuit exceeds say a mile or a mile and a half, difficulty is experienced in operating a multi-contact track relay by the comparatively weak energy that is received from the rails and resort then must be had to the repeater relay TM. As the drawing shows, this repeater relay carries the decoding control contacts 6-7 and it is energized locally under the control of a single contact 8 of the track relay TR.

When provided with this single contact only, relay TR picks up on a much smaller intensity of trackway energy than does a multi-contact device. The reduction in energy requirements is, in fact, so great that code following track relays of the single contact type (device TR of Fig. 1) can be operated with complete dependability over track circuits having lengths of two miles or more.

The repeater relay TM which makes this extended track circuit length possible may be picked up either over a back point of the track relay contact 8, as shown in Fig. 1, or over a front point of the track relay contact, as shown in Fig. 3. In both instances the decoding contacts 6-7 of relay TM repeat all code following operations of the controlling contact 8 of track relay TR. In the former, relay TM is released when relay TR is picked up and picked up when relay TR is released; in the latter, relay TM is picked up when relay TR is picked up and released when relay TR is released.

In order that the wayside signal Se may be kept dark as long as section D-E remains vacant and lighted only when a train places a shunt across the section rails, the lamp energizing circuits therefor are carried over a back contact 9 of an approach relay AR at the section exit E. This relay is slow releasing and as long as the winding thereof is recurrently energized at code speed rate, contact 9 occupies the picked up position wherein the signal circuits are disconnected from their lighting supply source.

Controlling this approach relay energization is a detector relay KR. Each time that a contact 11 thereof is picked up at a time when a contact 12 of the coding device CTM is released, relay AR is energized over a circuit that extends from the positive terminal of a local supply source, through

back contact 12, the winding of relay AR, front contact 11 of relay KR, and a "stick" winding 13 of that relay back to the negative terminal of the supply source. For a more complete description of this circuit reference may be had to a copending application Serial No. 354,097 filed by Herman G. Blosser on August 24, 1940.

The main or pick-up winding 15 of the detector relay KR is connected with the section rails during and only during the "master" code "off" periods. This connection is established at the back point of coding contact 5 and over it "off" period pulses of "feed back" current (from the section entrance D) are supplied to winding 15 as long as the section remains vacant. These pulses recurrently pick up the detector relay contact 11 and thereby cause the approach relay AR to keep signal Se deenergized.

These detector relay energizing pulses of feed back energy are supplied to the section rails by apparatus that is installed at the entrance location D. This apparatus comprises: (1) a source of "feed back" energy AB; (2) an impulse relay IR having a contact 17 for transferring the connection of the section rails 1-2 from the track relay TR to source AB during each "off" period of the received "master" code; and (3) a circuit over which a short pulse of pick-up current is supplied to the impulse relay IR at the beginning of each of the named "off" code periods.

The just-named impulse relay IR may be of the same type as the earlier mentioned Blosser Re-issue Patent No. 21,783 shows and describes. As long as the winding thereof remains deenergized, contact 17 stays released and connects the operating winding of track relay TR directly across the section rails. Upon energization of the impulse relay winding, however, contact 17 picks up and then transfers the connection of the section rails from the relay TR to the feed back energy source AB.

Through the use of a relay snubbing element 20 or other equivalent means, this contact 17 is provided with a period of release delay which while appreciable is somewhat less than the "off" period length of the fastest "master" code to which the track relay TR is called upon to respond. The reason for this limitation will become more apparent from later references to the code diagrams of Fig. 2.

The improvements of my invention reside in the circuit over which this impulse relay IR is picked up during each "off" period of the received master code. This pick-up circuit may be energized from any suitable local source, such as the terminals "plus" and "minus" designate, and in the form shown in Fig. 1 it includes a back contact 8 of the code following relay TR connected in series with a back contact 19 of the repeater relay TM.

Under conditions (section D-E vacant) of master code energy reception at location D: (1) the track relay TR holds contact 8 picked up during each "on" period of the received (from exit end source TB) master code and releases contact 8 during each "off" period interval of that code; and (2) the repeater relay TM keeps contact 19 released during each "on" period of the same received code and picks up contact 19 early during each "off" period of that code.

The pick-up circuit for impulse relay IR is, in consequence, kept deenergized (at contact 8) during each of those master code "on" periods and contact 17 of that relay then keeps relay TR

connected with the section rails in the desired manner.

Upon each "off" period release of relay TR, however, contact 8 of that relay reaches its released position before contact 19 of relay TM leaves its released position and thus energizes the impulse relay over a path that extends from the positive supply terminal through back contact 8, conductor 21, back contact 19, conductor 22 and the impulse relay winding back to the negative supply terminal.

This interval of pick-up circuit completion, while momentary, is sufficient to cause relay IR to move contact 17 to the picked up position in which the connection of the section rails is transferred from relay TR to the feed back energy source AB. Once so picked up, contact 17 there continues for the full release period of relay IR and thereby prolongs the resulting pulse of feed back trackway energy considerably beyond the point in the "off" code period that repeater relay contact 19 picks up and breaks the impulse relay pick-up circuit.

As previously stated, the period of release delay for the impulse relay IR is chosen to be somewhat less than the "off" period length of the fastest "master" code to which the track relay TR is called upon to respond. The reason for this choice will become evident upon inspection of Fig. 2.

As is there shown, each "feed back" energy pulse begins early in the "master" code "off" period during which it occurs. Were relay IR to be quick releasing, the feed back pulse would terminate upon interruption of the impulse relay pick-up circuit and thus be much shorter than is either necessary or desirable. By making relay IR slow releasing, the duration of the feed back pulse is prolonged to a point close to the "off" period end.

Never, however, may it extend beyond the end of the shortest master code "off" period, otherwise the track relay TR would still be disconnected from the section rails at the beginning of the succeeding "on" code period. Hence the release delay for relay IR always is kept within the limits previously stated.

Referring now to Fig. 3, I have there shown the entrance end apparatus of Fig. 1 modified to include a front contact repeater TM! for the code following track relay TR.

This repeater relay TM! is similar to device TM of Fig. 1 and differs therefrom only in that it receives pick-up current over the front point of track relay contact 8 and in that it is provided with a short period of release delay. Contacts 6, 7 and 19 thereof are picked up during each "on" period pulse of the received master code and are released during each "off" period interval of that code.

The impulse relay pick-up circuit of Fig. 3 includes (like the circuit of Fig. 1) back contact 8 of relay TR connected in series with contact 19 of the repeater relay TM!. In this Fig. 3 organization, however, contact 19 effects circuit completion when picked up and circuit interruption when released.

The control of impulse relay IR which the pick-up circuit of Fig. 3 exercises is the full equivalent of that explained for the organization of Fig. 1. Under conditions of master code reception relays TR and TM! are both picked up during each "on" period of the received master code and both released during each "off" period of that code.

The pick-up circuit for impulse relay IR is,

in consequence, deenergized (at contact 8) during each of those master code "on" periods and contact 17 of that relay then keeps relay TR connected with the section rails in the desired manner. Upon each "off" period release of relay TR, however, contact 8 of that relay reaches its released position before contact 19 of relay TM! leaves its picked up position and thus completes the pick-up circuit for the impulse relay.

In this manner relay IR is caused to pick up contact 17 early during each "off" period of the received master code. Even though contact 19 almost immediately releases (and interrupts the impulse relay pick-up circuit), contact 17 continues pick up until the expiration of the impulse relay delay period and thus continues the connection of feed back source AB with the section rails until close to the end of the "off" code period, as shown in Fig. 2.

Upon that relay expiration, contact 17 releases and by reconnecting the track relay TR with the section rails reconditions that relay for reception of and response to another "on" period pulse of master code energy.

In each of the just described Figs. 1 and 3 the impulse relay IR is arranged to disconnect the track relay TR from the section rails during each period of feed back source connection therewith. While this is a very desirable method of insuring the track relay against false pick-up during the "off" period intervals of feed back energy supply it is by no means the only method available for accomplishing the named result.

One alternative method is illustrated in Fig. 4. There the track relay TR is continuously connected with the section rails 1-2 through a static type of rectifier 24. This rectifier is poled in opposition to the polarity of the energy which feed back source AB supplies to the rails when contact 17 of the impulse relay IR is picked up and in consequence current from source AB is excluded from the track relay winding as effectively as were that winding to be disconnected from the rails at the back point of contact 17, as in Figs. 1 and 3.

Quite obviously the impulse relay IR of Fig. 4 may have exactly the same characteristics as in either of Figs. 1 and 3 and may be operated over the pick-up circuit which each of those two figures shows. The improved pick-up circuit of my invention, therefore, is not limited to impulse relays which disconnect the code following relay from the control circuit conductors during the "off" code periods but may be used with any impulse relay that connects a feed back source with those conductors when picked up and breaks that connection when released.

The improved impulse relay control facilities of my invention are, moreover, not restricted to control circuits of the track type herein disclosed but they also have utility when applied to "coded feed back" circuits of any other form wherein the conductors lose their normal energy transmitting capability under certain conditions only.

Thus, instead of being track rails as shown, the control circuit conductors 1-2 may also take the form of line wires which connect master energy supply and feed back energy receiving equipment (see device TB-CTM-KR of Fig. 1) at one end of the circuit with master energy receiving and feed back energy supply equipment (see devices TR-TM-AB-IR of Fig. 1) at the other end of the circuit.

When used with a control circuit of the line

conductor type just described an impulse relay equipped with the improved pick-up circuit facilities of my invention will function in exactly the same manner as when used with the track type of control circuits that are herein disclosed. My invention is, therefore, one of broad utility and is not to be restricted to the specific forms or applications that I have shown by way of illustration.

From the foregoing description of Figs. 1 to 4, therefore, it will be seen that I have made important contributions to control circuit combinations of the "coded feed back" class. In particular I have improved the organization of the apparatus by which the conductors of such circuits are supplied with "off" period pulses of feed back energy; I have facilitated the control of feed back energy applying relays of the "impulse" or IR type; and I have simplified and increased the power economy of pick-up circuits for such impulse relays when those relays are used with control circuit combinations wherein the "master" energy operated relay is supplemented by a code following repeater.

Although I have herein shown and described only three forms of railway traffic controlling apparatus embodying my invention, it is understood that various changes and modifications may be made therein within the scope of the appended claims without departing from the spirit and scope of my invention.

Having thus described my invention, what I claim is:

1. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by and only by each of the said "on" period pulses of master code energy that said connection transmits, a repeater relay controlled by said code following relay and occupying a first position when the code following relay is picked up but shifting after a slight delay to a second position upon each release of the code following relay, a source of feed back energy, an impulse relay which in picking up connects said feed back energy source with said control circuit conductors and which in releasing interrupts that connection, an energizing circuit for said impulse relay which includes a back contact of said code following relay connected in series with a contact of said repeater relay that is closed in said first position and over which each release of said code following relay contact momentarily picks up the impulse relay and thereby causes said circuit conductors to be supplied with a pulse of feed back energy during the "off" code period of said release; and traffic governing apparatus controlled by the pulses of said feed back energy which said circuit conductors transmit.

2. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by and only by each of the said "on" period pulses of master code energy that said connection transmits, a repeater relay energized over a back contact of said code following relay and occupying a released position when the code following relay is picked up but shifting after a slight delay to a second position upon each release of the code following relay, a source of feed back energy, an impulse relay which in picking up connects said feed back energy source with said control circuit conductors and which in releasing interrupts that connection, an energizing circuit for said impulse relay which includes a back contact of said code following relay connected in series with a contact of said repeater relay that is closed in said first position and over which each release of said code following relay contact momentarily picks up the impulse relay and thereby causes said circuit conductors to be supplied with a pulse of feed back energy during the "off" code period of said release; and traffic governing apparatus controlled by the pulses of said feed back energy which said circuit conductors transmit.

3. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position upon each release of the code following relay, a source of feed back energy, an impulse relay which in picking up connects said feed back energy source with said control circuit conductors and which in releasing interrupts that connection, an energizing circuit for said impulse relay which includes a back contact of said code following relay connected in series with a contact of said repeater relay that is closed in said first position and over which each release of said code following relay contact momentarily picks up the impulse relay and thereby causes said circuit conductors to be supplied with a pulse of feed back energy during the "off" code period of said release; and traffic governing apparatus controlled by the pulses of said feed back energy which said circuit conductors transmit.

4. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by and only by each of the said "on" period pulses of master code energy that said connection transmits, a repeater relay controlled by said code following relay and occupying a front contact of said code following relay and a back contact of said repeater relay connected in series with a front contact of said repeater relay and over which each release of said code following relay contact momentarily picks up the impulse relay and thereby causes said circuit conductors to be supplied with a pulse of feed back energy during the "off" code period of said release; and traffic governing apparatus controlled by the pulses of said feed back energy which said circuit conductors transmit.

5. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by and only by each of the said "on" period pulses of master code energy that said connection transmits, a repeater relay controlled by said code following relay and occupying a first position when the code following relay is picked up but shifting after a slight delay to a second position upon each release of the code following relay, a source of feed back energy, an impulse relay which in picking up transfers the connection of said control circuit conductors from said code following relay to said feed back energy source and which in releasing restores the control circuit connection to the code following relay, an energizing circuit for said impulse relay which includes a back contact of said code following

relay connected in series with a contact of said repeater relay that is closed in said first position and over which each release of said code following relay contact momentarily picks up the impulse relay and thereby causes said circuit conductors to be supplied with a pulse of feed back energy during the "off" code period of said release, and traffic governing apparatus controlled by the pulses of said feed back energy which said circuit conductors transmit.

5. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay controlled by said code following relay and occupying a first position when the code following relay is picked up but shifting after a slight delay to a second position upon each release of the code following relay, a source of feed back energy, an impulse relay having a release delay which is appreciable but less than the "off" period length of said master code and provided with a contact which in picking up transfers the connection of said control circuit conductors from said code following relay to said feed back energy source and which in releasing restores the control circuit connection to the code following relay, a pick-up circuit for said impulse relay which includes a back contact of said code following relay connected in series with a contact of said repeater relay that is closed in said first position and over which each release of said code following relay contact momentarily energizes the impulse relay and thereby causes said circuit conductors to be supplied with a pulse of feed back energy during the "off" code period of said release, and traffic governing apparatus controlled by the pulses of said feed back energy which said circuit conductors transmit.

6. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay energized over a back contact of said code following relay and occupying a released position when the code following relay is picked up but shifting after a slight delay to a picked up position upon each release of the code following relay, a source of feed back energy, an impulse relay which in picking up transfers the connection of said control circuit conductors from said code following relay to said feed back energy source and which in releasing restores the control circuit connection to the code following relay, an energizing circuit for said impulse relay which includes a back contact of said code following relay connected in series with a back contact of said repeater relay and over which each release of said code following relay contact momentarily picks up the impulse relay and thereby causes said circuit conductors to be supplied with a pulse of feed

back energy during the "off" code period of said release, and traffic governing apparatus controlled by the pulses of said feed back energy which said circuit conductors transmit.

5 7. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay energized over a back contact of said code following relay and occupying a released position when the core following relay is picked up but shifting after a slight delay to a picked up position upon each release of the code following relay, a source of feed back energy, an impulse relay having a release delay which is appreciable but less than the "off" period length of said master code and provided with a contact which in picking up transfers the connection of said control circuit conductors from said code following relay to said feed back energy source and which in releasing restores the control circuit connection to the code following relay, a pick-up circuit for said impulse relay which includes a back contact of said code following relay connected in series with a back contact of said repeater relay and over which each release of said code following relay contact momentarily energizes the impulse relay and thereby causes said circuit conductors to be supplied with a pulse of feed back energy during the "off" code period of said release, and traffic governing apparatus controlled by the pulses of said feed back energy which said circuit conductors transmit.

40 8. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay energized over a front contact of said code following relay and occupying a picked up position when the code following relay is picked up but shifting after a slight delay to a released position upon each release of the code following relay, a source of feed back energy, an impulse relay which in picking up transfers the connection of said control circuit conductors from said code following relay to said feed back energy source and which in releasing restores the control circuit connection to the code following relay, an energizing circuit for said impulse relay which includes a back contact of said code following relay connected in series with a front contact of said repeater relay and over which each release of said code following relay contact momentarily picks up the impulse relay and thereby causes said circuit conductors to be supplied with a pulse of feed back energy during the "off" code period of said release, and traffic governing apparatus controlled by the pulses of said feed back energy which said circuit conductors transmit.

9. In a railway signaling system, the combina-

tion of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay energized over a front contact of said code following relay and occupying a picked up position when the code following relay is picked up but shifting after a slight delay to a released position upon each release of the code following relay, a source of feed back energy, an impulse relay having a release delay which is appreciable but less than the "off" period length of said master code and provided with a contact which in picking up transfers the connection of said control circuit conductors from said code following relay to said feed back energy source and which in releasing restores the control circuit connection to the code following relay, a pick-up circuit for said impulse relay which includes a back contact of said code following relay connected in series with a front contact of said repeater relay and over which each release of said code following relay contact momentarily energizes the impulse relay and thereby causes said circuit conductors to be supplied with a pulse of feed back energy during the "off" code period of said release, and traffic governing apparatus controlled by the pulses of said feed back energy which said circuit conductors transmit.

10. In a railway signaling system, the combination of a control circuit which comprises a pair of conductors, means for supplying said conductors with master code energy in the form of recurring "on" period pulses that are separated by "off" period intervals, a code following relay connected with said conductors and operated from a released to a picked up position by each of the said "on" period pulses of master code energy that said connection transmits, a repeater relay controlled by said code following relay and occupying a first position when that relay is picked up but shifting after a slight delay to a second position when the code following relay releases, a source of feed back energy, an impulse relay which in picking up connects said feed back energy source with said control circuit conductors and which in releasing interrupts that connection, an energizing circuit for said impulse relay which includes a back contact of said code following relay connected in series with a contact of said repeater relay that is closed in said first position and over which each release of said code following relay contact momentarily picks up the impulse relay and thereby causes said circuit conductors to be supplied with a pulse of feed back energy during the "off" code period of said release, means effective during each of said "off" code periods for preventing the said feed back energy that is then impressed upon the circuit conductors from picking up said code following relay, and traffic governing apparatus controlled by the pulses of said feed back energy which said circuit conductors transmit.

11. In a railway signaling system, the combination of a control circuit comprising a pair of conductors which normally are capable of trans-

mitting energy between given and opposite ends of the circuit but which at times are rendered incapable of such transmission, means at the given end of said circuit for supplying said conductors with master code energy in the form of recurring "on" period pulses that are separated by "off" period intervals, a code following relay at the opposite end of said circuit connected with said conductors and operated from a released to a picked up position by each of the said "on" period pulses of master code energy that said conductors transmit, a repeater relay controlled by said code following relay and occupying a first position when the code following relay is picked up but shifting after a slight delay to a second position upon each release of the code following relay, a source of feed back energy at said opposite circuit end, an impulse relay also at said opposite end which in picking up transfers the connection of said control circuit conductors from said code following relay to said feed back energy source and which in releasing restores the control circuit connection to the code following relay, an energizing circuit for said impulse relay which includes a back contact of said code following relay connected in series with a contact of said repeater relay that is closed in said first position and over which each release of said code following relay contact momentarily picks up the impulse relay and thereby causes said control circuit conductors to be supplied with a pulse of feed back energy during the "off" code period of said release, and traffic governing apparatus at said given circuit end controlled by the pulses of said feed back energy which are there received and selectively responsive according as said pulse reception does or does not continue.

12. In a railway signaling system, the combination of a section of track, means at the exit end of said section for supplying the section rails with master code energy in the form of recurring "on" period pulses that are separated by "off" period intervals, a code following track relay at the entrance end of said section connected with said rails and operated from a released to a picked up position by each of the said "on" period pulses of master code that said rails transmit, a repeater relay controlled by said track relay and occupying a first position when the track relay is picked up but shifting after a slight delay to a second position upon each release of the track relay, a source of feed back energy at said section entrance end, an impulse relay also at said opposite end which in picking up transfers the connection of said rails from said track relay to said feed back energy source and which in releasing restores the rail connection to the track relay, an energizing circuit for said impulse relay which includes a back contact of said track relay connected in series with a contact of said repeater relay that is closed in said first position and over which each release of said track relay contact momentarily picks up the impulse relay and thereby causes said rails to be supplied with a pulse of feed back energy during the "off" code period of said release, and traffic governing apparatus at said section exit controlled by the pulses of said feed back energy which are there received and selectively responsive according as said pulse reception does or does not continue.

FRANK H. NICHOLSON.
